United States Patent Office.

WILLIAM A. GAY. OF NEWARK, NEW JERSEY.

Letters Patent No. 99,077, dated January 25, 1870.

GRAVEL-HEATER

The Schedule referred to in these Letters Patent and making part of the same.

To all whom it may concern:

Be it known that I, WILLIAM A. GAY, of Newark, in the county of Essex, and State of New Jersey, have invented a new and useful Improvement in Gravel-Heater; and I do hereby declare that the following is a full, clear, and exact description thereof, which will enable others skilled in the art to make and use the same, reference being had to the accompanying drawings, forming part of this specification.

This invention relates to a new and useful improvement in apparatus for heating gravel, for roofing, concrete pavements, and for all the purposes to which it is adapted; and

It consists in the construction and arrangement hereinafter described.

In the accompanying drawing—

Figure 1 is a vertical longitudinal section of fig. 2, through the line *x x*.

Figure 2 is a top or plan view.

Figure 3 is a vertical cross-section through the line *y y* of fig. 2.

Similar letters of reference indicate corresponding parts.

This apparatus consists of a rectangular-shaped casing, A, of suitable size, (in length, breadth, and depth,) with an interior arrangement of inclined and vertical plates, for enclosing the fire and conveying the heat to the gravel, with interior guide-flanges and discharge-apertures for the gravel.

The casing A is open at top and bottom, the fire being made or supported on the ground.

B is the furnace-door;

C, the fire-chamber; and

D, the combustion-chamber, the sides of which may be perforated, as seen in fig. 1, at *i*.

The whole apparatus is made of sheet-metal, preferably, and the sides of the combustion-chamber D are perforated, by means of punching from the inner sides of those plates, which leaves their outer sides with projecting collars around each hole, as on the surface of the ordinary grates, which prevent the particles of gravel from readily entering holes.

E represents the space which is occupied by the gravel, when it is being heated.

F is the pipe, for the discharge of the smoke.

G is a damper in the smoke-pipe.

H represent the apertures, for the discharge of the gravel. These apertures are narrow openings, extending the whole length of the apparatus on each side.

I represent flanges on the insides of the casing or

side walls, the tendency of which is to guide the gravel on to the inclined furnace-plates J J.

The gravel to be heated is introduced at the top. A portion of the gravel will at first pass through the discharge-apertures H, and bank up, but as those apertures are near the ground, they will soon be filled, and then the gravel will fill the space E, on each side of the combustion-chamber.

The gravel which rests over the plates J will soon become heated. The small banks of gravel at the sides are shovelled back into the heater, and the heated gravel, ready for use, will slide from the plates J, and be discharged.

The flanges I serve to throw the descending gravel in a thin layer on to the hot plates J, so that when the gravel is discharged at H, it is thoroughly heated.

The perforations *i*, through the sides of the combustion-chamber D, allow the heat to penetrate the mass of gravel in the spaces E.

It will be seen that as the gravel is fed in at the top, the mass is constantly settling and being discharged. This heater being made of sheet-metal is light and portable. The large heating-surface exposed, and the manner in which the gravel is projected upon the heated furnace-plates, renders it economical of fuel, and admirably adapted for the purposes intended.

By closing (or nearly closing) the damper G, after the fire is once well going, the combustion may be continued, and the main portion of the heat retained for a long time.

I do not confine myself to any particular size or position for the guide-flanges I, nor to perforating the sides of the combustion-chamber D.

Having thus described my invention,

I claim as new, and desire to secure by Letters Patent—

1. In combination with an apparatus for heating gravel, the fire-chamber C and the combustion-chamber D, either with or without the perforation *i*, arranged substantially as described.

2. The flanges I, substantially as and for the purposes described.

3. The combination of the heating-plates J J, the guide-flanges I, and the discharge-apertures H, substantially for the purposes described.

The above specification of my invention signed by me, this 23d day of November, 1869.

WM. A. GAY.
